UNITED STATES PATENT OFFICE.

WILLIAM L. LUKENS AND JOHN A. TAYLOR, OF BETHLEHEM, PENNSYLVANIA, AS
SIGNORS TO BETHLEHEM STEEL COMPANY, OF BETHLEHEM, PENNSYLVANIA, A
CORPORATION OF PENNSYLVANIA.

FUSE FOR PROJECTILES.

Application filed September 20, 1922. Serial No. 589,434.

To all whom it may concern:

Be it known that we, WILLIAM L. LUKENS and JOHN A. TAYLOR, citizens of the United States, and residents of Bethlehem, Northampton County, State of Pennsylvania, have invented certain new and useful Improvements in Fuses for Projectiles, of which the following is a specification.

This invention relates to artillery ammunition and particularly to projectiles having point detonating fuses of the adjustable type.

The object of the invention is to provide a projectile which has a fuse of the adjustable type enclosed therein but adapted to be adjusted from without, through an aperture in the projectile wall, to give different speeds of action. The fuse utilized in combination with the projectile is of novel construction and is adapted to be adjusted to effect the detonation of the projectile bursting charge either before the projectile body strikes the target, at the instant the projectile body strikes the target, or after the projectile body strikes the target. The projectile within which the fuse is enclosed is provided with an axial aperture in its point and through this aperture extends the means by which the speed of action of the fuse may be adjusted. The fuse is provided with safety devices to prevent premature explosion and the parts are so arranged that the projectile is properly balanced, has a satisfactory outline for keeping the wind resistance at a minimum, and is simple in construction.

One embodiment of the invention will be disclosed by way of example in the following description when taken with the accompanying drawings, but it will be understood that the principles involved may be carried out in various ways.

In the drawings:

Figure 1 is an axial longitudinal section through the forward portion of an explosive projectile having the novel fuse and fuse adjusting means incorporated therein, the fuse being adjusted for delayed action and the parts being shown in the positions which they occupy before the projectile is fired from the gun;

Figure 2 is a similar view showing the positions of the parts after the projectile has struck a target;

Figure 3 is a view similar to Figure 2 but showing the positions of the parts of the fuse after striking a target where the fuse has been adjusted previously to firing, to give immediate detonation instead of a delayed detonation;

Figure 4 is a view similar to Figure 3 but showing the fuse parts in the positions which they occupy upon impact, where the fuse has been adjusted to act before the body of the projectile reaches the target;

Figure 5 is a section on line 5—5 of Figure 2; and

Figure 6 is a section illustrating the delay element.

The hollow projectile body is indicated at 10 and its ogival nose is shown at 11, the adjacent ends of these portions having threaded engagement with the internally and externally threaded adapter 12. The adapter 12 supports the fuse F, the cylindrical rear portion of the head 13 of the fuse having threaded engagement with the inner wall of the adapter. The body portion 14 of the fuse is of less diameter than the head and extends into and has threaded engagement with the axial recess in the rear portion of the head.

The ogival point 11 of the projectile is provided with a circular axial aperture in its point and a plug 15 extends into this aperture, this plug being provided with retaining springs 16 which engage in recesses 17 so that the plug is held frictionally in position, but may be removed manually from the aperture in which it normally rests. The body portion of the fuse is formed substantially in the manner described and claimed in Patent No. 1,250,919 issued to J. P. Madden and W. L. Lukens, December 18, 1917.

The head of the fuse is substantially cylindrical, though tapering externally at its extreme forward end so as to clear the inner wall of the point 11. The axial opening in the head is also substantially cylindrical although having three sections of different diameter, the front section having the smallest diameter. As before stated, the forward end of the fuse body 14 has threaded engagement with the wall of the axial recess in the head of the fuse. Positioned between the oppositely facing shoulders of the head and body of the fuse are abutting disks 19 and

20, each of which is centrally apertured to provide a continuous flame passage. Disk 19 has threaded engagement with the body 14 of the fuse and serves to retain within the body the centrifugal cage 21 and the plunger 22, these members being positioned in communicating coaxial chambers in the fuse body, as pointed out in the prior patent referred to. Disk 20 serves to retain within the recess in the head of the fuse, the movable parts therein contained, when the head is disassociated from the base or body.

A firing pin carrier is indicated at 23 having secured thereto the firing pin 24, and being slidably retained within the axial recess in the fuse head. Also slidably contained within the recess in the head of the fuse is the primer carrying block or cylinder 25. Normally these members are prevented from approaching each other by means of the centrifugal locking bolts 26 which are urged inwardly by springs 27. A creep spring 28 is also interposed between the slidable firing pin carrier and the primer carrier, and opposes movement of these members toward each other. The primer is indicated at 29, a flash port bolt at 30, and flash powder at 31 and 32. It will be seen that as the parts are illustrated in Figure 1, the flash port bolt 30 blocks direct communication between the flash powder 31 and 32.

An enlarged section of the primer carrier is shown in Figure 6 and it will be seen from this drawing that the aperture 35 in the flash port bolt is normally in communication with a chamber containing a delay pellet 36 which chamber in turn communicates by means of an aperture 37 with the flash powder 32. A spring 39 normally tends to move the flash port bolt 30 to such position that the port or conduit 40 in this bolt provides a direct passage between the flash powder 31 and 32 as shown in Figures 3 and 4. Normally, however, the flash port bolt is locked against movement by a cotter pin 41 which extends through apertures in the primer carrier and flash port bolt and is connected by means of a cord 42 to the plug 15. When the cotter pin 41 has been withdrawn, which may be accomplished by pulling out the plug, the flash port bolt will move into the position in which it is shown in Figure 3 so that ignition of the primer will result in immediate ignition of the flash powder 31 and 32 and hence of the detonating charge of the fuse.

When it is desired to bring about the explosion of the projectile before the nose has struck the target the plug 15 and cotter pin 41 are completely withdrawn and the anticipator pin 43 inserted through the aperture in the point. This anticipator has a recess in its end adapted to receive a boss 44 projecting axially forward from the firing carrier. A retaining spring 45 on the boss en-

gages within apertures in the pin to hold the same functionally in position. If the projectile armed with the anticipator has normal impact with the target the firing pin carrier is thrust rearwardly, as shown in Figure 4 and the projectile exploded before the nose proper has struck the target. If the projectile strikes the target a glancing blow, so that the anticipator is not pushed rearwardly, the fuse functions by the forward movement of the primer carrier, as before.

When the projectile is first fired from a gun, and during the period when it is being accelerated, the firing pin carrier will, due to its inertia, exert a force on each of the centrifugal inertia bolts sufficient to prevent them from moving radially outward and arming the fuse. After acceleration ceases the force thus exerted by the firing pin carrier becomes zero and the bolts will be thrown outwardly. In the meanwhile however the projectile has passed out of the gun and the danger of a premature explosion in the gun barrel avoided.

The possibilities of the invention and its advantages in use, will be apparent to one skilled in the art. The design and arrangement of the parts of the fuse may be changed without departing from the spirit of the invention.

Having thus described the invention what is claimed as new and desired to be secured by Letters Patent is:

1. The combination with a hollow projectile body having an aperture in the wall portion thereof of a fuse completely enclosed within said projectile body rearwardly of the point of the latter, said fuse including means whereby it may be adjusted to different speeds of action upon impact of the projectile, and means removably secured in said opening and operatively connected to the said means for controlling the latter.

2. The combination with a hollow projectile body having an aperture in the wall thereof of a fuse completely enclosed within said projectile body rearwardly of the point of the latter, said fuse including means whereby it may be adjusted for different speeds of action upon impact of the projectile, a cord connected to said means, and a plug removably secured in said opening and connected to the cord and serving when removed to effect operation of said means.

3. The combination with a hollow projectile body having an aperture in the wall thereof of a fuse completely enclosed within said projectile body and disposed rearwardly of the point of the latter, said fuse including means whereby it may be adjusted for different speeds of action upon impact of the projectile, a member engaging said means and holding the same in one po-

sition of adjustment, a plug removably secured in said opening, and connecting means between the plug and said holding means, whereby, when the plug is removed, the holding means is rendered ineffective.

5 4. The combination with a hollow projectile body having an aperture in the wall thereof of a fuse completely enclosed within said projectile body, said fuse including 10 means whereby it may be adjusted for different speeds of action upon impact of the projectile, a pin engaging said means and holding the same in one position of adjustment, means for biasing said means to its 15 other position of adjustment, and a plug secured in said opening and connected to said pin, whereby removal of said plug effects movement of said pin and adjustment of the fuse.

20 5. The combination with a hollow pointed projectile body having an axial aperture in the point, of a fuse completely enclosed within said projectile body, said fuse including means whereby it may be adjusted for different speeds of action upon impact of the projectile, a pin engaging said means and holding the same in one position of adjustment, spring means for moving said first means to a second position of adjustment, a 25 plug removably secured in said opening, and a flexible cord connecting the plug and pin whereby removal of the plug effects movement of said pin and adjustment of the fuse.

30 6. The combination with a hollow projectile body having an aperture in the point thereof, of a fuse completely enclosed within the projectile wall, said fuse including means whereby it may be adjusted for different speeds of action, said fuse being relatively remote from the pointed end of the projectile, and an anticipator insertable through said aperture and arranged to engage the fuse when inserted, whereby the 35 fuse is caused to function before the nose of the projectile strikes the target.

7. The combination with a hollow projectile body having an aperture in the point thereof, of a fuse completely enclosed within the projectile wall and adapted to be adjusted for different speeds of action and having a movable firing pin carrier at its forward end, and an anticipator extending through the aperture in the projectile wall 50 and detachably secured to the firing pin carrier whereby the firing pin and the fuse may be caused to function before the projectile wall strikes the target.

8. The combination with a hollow projectile body having an aperture in the point

thereof, of a fuse completely enclosed within the projectile wall and adapted to be adjusted for different speeds of action and having a centrally arranged axially slideable firing pin carrier at its forward end, and 55 an anticipator extending through the aperture and detachably secured to the firing pin carrier, said anticipator also extending in advance of the projectile wall, whereby the firing pin and fuse may be caused to function before the projectile wall strikes the target.

9. In a fuse, the combination of a head portion having a bore, a closure for the rear of the bore connected to the head portion and 70 having a flash opening therein, a carrier movable in the bore, a forward flash charge carried by the carrier, a rearward flash charge carried by the carrier, a primer contiguous to the forward flash charge, a delay 75 charge carried by the carrier and communicating with the rearward flash charge, means movable transversely of the carrier to afford communication directly between the flash charges or between the forward flash 80 charge and the delay charge, a firing pin disposed forwardly of the carrier and in line with the primer, and means for normally holding the carrier in the rear portion of the bore and responsive to centrifugal force to 85 permit the carrier to pass thereby.

10. In a fuse, the combination of a head portion having a longitudinal bore, a primer carrier having a transverse passage, flash charges disposed forwardly and rearwardly 90 of the transverse passage, a primer arranged contiguous to and forwardly of the forward flash charge, a delay charge disposed laterally of the passage and adapted to communicate with the rear flash charge, a member 95 movable in the transverse passage and having a passageway to afford communication between the flash charges in one position of said member and a passageway for affording communication between the forward flash 100 charge and the delay charge in another position of said member, means for biasing the member to the first position, removable key means for holding said member in the second position, means for normally holding the 105 carrier at the rear of the bore and responsive to centrifugal force to allow the carrier to move thereby, and a firing pin disposed at the forward end of the bore and in line with the primer.

115 In testimony whereof we hereunto affix our signatures.

WILLIAM L. LUKENS.
JOHN A. TAYLOR.
